UNITED STATES PATENT OFFICE.

WILLIAM RIGHTER COMINGS, OF WIMBLEDON PARK, ENGLAND.

HAND EMBROIDERER.

1,410,891.

Specification of Letters Patent. Patented Mar. 28, 1922.

Application filed April 1, 1920. Serial No. 370,442.

To all whom it may concern:

Be it known that I, WILLIAM R. COMINGS, a citizen of the United States, residing at Wimbledon Park, Surrey, England, have invented certain new and useful Improvements in Hand Embroiderers, of which the following is a specification.

My invention relates to that type of devices known as hand embroiderers, and has 10 for its object to provide certain improvements in the foot pieces of said devices, which consists in forming the same of transparent material, such as celluloid, whereby the operator may have an unobstructed view of 15 the needle, during the operation of the machine.

In the drawings:—

Figure 1 is a side elevation of the lower 20 end of a hand embroiderer equipped with my improved foot piece.

Figure 2 is a detail perspective view of the foot piece and its base, shown separated.

Figure 3 is a top plan view of said base.

In said drawing, the reference numeral 25 1 denotes the lower end of the casing of the device in which the carrier for the needle 2 is located, said casing being formed circular, as shown, though its shape in this particular is immaterial. Clamped to the lower end 30 of said casing, by means of a collar 3 and a screw-bolt 4 passing through the ears 5 of said collar, is a foot piece 6, the same being shaped slightly flaring towards its lower end, and formed of some transparent ma-

terial, preferably celluloid. Fitted to the 35 bottom of said foot piece 6 is a base 7, also formed of transparent material, such as celluloid, and shaped with an upstanding flange 8, so as to form a cup adapted to engage the lower edge of said foot piece 6, as shown. 40 This base is provided with a central aperture 9, through which the needle 2 of the embroiderer is adapted to reciprocate in the usual manner. It will be observed that this aperture 9 is just large enough to permit 45 the free passage of the needle and the thread carried thereby, whereby any drawing up of the fabric being operated on during the upward drawing movement of the needle most effectually is minimized. This construction is rendered possible by reason of 50 the fact that the foot piece 6 and base 7 both are made of transparent material, affording an unobstructed view of the needle in any position of the parts during operation, and 55 thus avoiding the necessity for a comparatively large aperture in the base 7.

Having thus described my invention, what I claim as new and desire to secure by Letters Patent, is:—

A hand embroiderer, comprising a needle carrying casing, a foot piece clamped to said casing, and a circular base fitted to said foot piece and apertured for the passage of the needle, said foot piece and base being formed 65 of transparent material.

In testimony whereof I affix my signature.
WILLIAM RIGHTER COMINGS.
